UNITED STATES PATENT OFFICE.

CHAUNCEY L. OLMSTEAD, OF WEST BROOKFIELD, AND ALBERT D. NASON,
OF SPRINGFIELD, MASSACHUSETTS.

DESIGN FOR A CORSET.

SPECIFICATION forming part of Design No. 17,388, dated June 14, 1887.

Application filed April 4, 1887. Serial No. 233,656. Term of patent 14 years.

To all whom it may concern:

Be it known that we, CHAUNCEY L. OLMSTEAD, of West Brookfield, county of Worcester, State of Massachusetts, and ALBERT D. NASON, of Springfield, in the county of Hampden and State of Massachusetts, have invented a new Design for Corsets; and we do hereby declare the following, when taken in connection with accompanying drawing, and the letters of reference marked thereon, to be a full, clear, and exact description of the same, and which said drawing constitutes part of this specification, and represents one-half of a corset.

15 This invention relates to a design for the ornamentation of corsets; and it consists in the ornamentation as shown in the accompanying illustration.

On the side of the corset, under the arms, and what is called the "hip-section," there is the representation of a vertical series of ribs, A, near the front edge of the section, extending from top to bottom, and upon the rear side of the center of the hip-section is the representation of a similar series of vertical ribs, B, extending from top to bottom. At the center, side, and between the two series of ribs A. B, represented as aforesaid, is the representation of a series of transverse ribs, C, the series of 25 ribs extending from the top of the corset down to about the waist-line and between the two series of ribs A. B from the lower end of the transverse ribs C to the bottom of the corset represents a Shirred surface. From the front 30 edge of the series A, and at the bottom of the corset, there is the representation of a series of ribs, D, running downward and forward, following the line of the lower edge of the corset to the front. In the central breast is the 35 representation of a series of vertical ribs, E, running from the top of the corset down to the series of ribs D, and between the breast portion and the series of ribs A is the representa-

tion of two parallel series of ribs, F G, running from the top of the corset down to the 45 series of ribs C. At the back—that is, between the hip-section and the rear section—is the representation of two series of ribs, H I, running from top to bottom, forming one series from the waist-line up, but diverging from 50 each other from the waist-line downward to the bottom of the corset, all as shown in the accompanying illustration.

We claim—

The herein described design for corset, consisting of the representation upon the side of the corset of a series of vertical ribs, A, and a similar series of vertical ribs, B, extending from the top of the corset to the bottom, with the representation of a transverse series of 60 ribs, C, between the two series A B, extending from the top of the corset to about the waist-line, and from the bottom of the series of ribs C, between the two series of ribs A B, to the bottom of the corset is the representation 65 of a Shirred surface, and with the representation of a series of ribs, D, running from the side downward and forward, following the line of the bottom of the corset to the front, the representation of a vertical series of ribs running from the top of the corset centrally through 70 the breast to the said series D, and the representation of two parallel series of ribs, F G, between the front and side, running from the top of the corset down to the series D, and 75 with the representation of two series of ribs, H I, on the back of the corset, running from top to bottom, diverging from about the waist-line downward, as shown in the accompanying illustration.

CHAUNCEY L. OLMSTEAD.
ALBERT D. NASON.
